VIBRATORY REED DRIVE

David Hancock, Jr., Chicago, Ill., assignor to
Hammond Instrument Company, Chicago, Ill.,
a corporation of Delaware

Application May 1, 1941, Serial No. 381,878

8 Claims. (Cl. 172—126)

My invention relates generally to vibrators, and more particularly to improvements in electromagnetic driving means for vibratory reeds.

It is an object of my invention to provide an improved electromagnetic driving means for vibratory reeds which is effective automatically to limit the amplitude of vibration of the reed.

A further object is to provide an improved electromagnetically driven vibratory reed in which the electromagnetic driving means also serves as a brake to retard the vibration when the amplitude of vibration of the reeds exceeds a predetermined value.

Other objects will appear from the following description, reference being had to the accompanying drawing in which:

Figure 1 is a plan view of the vibratory reed and driving means therefor;

Figure 2 is an elevational view thereof;

Figure 3 is an enlarged fragmentary sectional view taken on the line 3—3 of Fig. 2;

Figure 4 is a fragmentary sectional view similar to Fig. 3 showing the contact parts in displaced position, the extent of displacement being exaggerated;

Figure 5 is an enlarged fragmentary sectional view taken on the line 5—5 of Fig. 1;

Figure 6 is a wiring diagram; and

Figure 7 is a diagram illustrating the method and operation of the apparatus.

The invention may be employed generally for the maintenance in vibration of a vibratory element such as a reed, but is disclosed herein as employed in the vibrato mechanism of an electrical musical instrument. Such vibrato mechanism is more fully disclosed in the co-pending application of Laurens Hammond, Serial No. 362,018, filed October 21, 1940.

Referring to Figs. 1 and 2, the vibrato mechanism comprises generally a ferromagnetic part 10 which is securely riveted to a leaf spring 12, while the latter is rigidly attached to the upwardly extending portion of a bracket 14 suitably mounted on a supporting plate 16. The leaf spring 12 together with the part 10 thus composes a freely vibratory reed.

Rigidly secured to the part 10 is a core 18 preferably of the powdered iron type, a plurality of washers 20 being likewise secured to the part 10 to provide the necessary mass to obtain the desired frequency of vibration. Additional washers may be added, or some of the washers shown may be removed, for adjustment of the mass of the reed. The desired frequency of vibration of

the reed may be obtained in any other suitable way.

The core 18, upon vibration of the reed, oscillates in the hollow center of a coil 22 which, as disclosed in the aforesaid application to Laurens Hammond, may be located in the tuning circuit of an oscillator, and by the variation in its inductance may vary the frequency of an oscillator. The coil 22 may, however, be utilized for any other form of electrical control which may be desired. Or, by making the core 18 in the form of a permanent magnet, the coil 22 and such magnet may form a pickup to transmit electrical oscillations of the reed vibration frequency to any electrical apparatus for such frequency as may be utilized. Alternatively, the reed may be provided with contacts to make and break external circuits.

A contact strip 24 and an insulating strip 26 are riveted to the opposite sides of the part 10 adjacent its connection to the leaf spring 12, both of these strips extending beyond the lower edge of the part 10. A contact arm 28 has its end portion 30 formed in a vertical plane, and has a horizontally extending contact wire 32 welded or otherwise suitably secured thereto. The contact wire 32 is cooperable with a similar vertically extending contact wire 34 which is welded or otherwise secured adjacent the formed lower end of the contact strip 24. The arm 28 is mounted for rotation between a pair of insulating friction washers 36, 37, the washer 36 being shouldered to provide a flange 38 forming a central bearing for the arm 28. The arm 28 is clamped with light pressure between the two washers 36 and 37 by the force applied by a compression coil spring 40 which is compressed between the washer 36 and a washer 42. A spacing sleeve 44 is clamped between the washer 42 and a similar washer 46 by a bolt 48 which also passes through the mounting plate 16 and thus rigidly secures the pivoted assembly for the arm 28. The degree of compression of the spring 40 is such that the frictional torque resisting oscillation of the arm 28 is sufficiently great to cause this arm to remain in any position to which it is moved, but is insufficient to place a material load upon the vibratory reed.

Referring to Figs. 3 and 4, it will be apparent that when the reed is moving on the counter-clockwise portion of its vibratory cycle, the insulating strip 26 will contact the end portion 30 of the arm 28 and swing the latter counterclockwise with the reed.

Upon the commencement of the clockwise por-

tion of the vibratory cycle of the reed, the arm 28 will remain stationary for a short interval of time until the contact wire 34 engages the contact wire 32, whereupon the arm 28 will be carried with the reed throughout the remainder of the clockwise stroke of the reed. Immediately upon commencement of the counterclockwise stroke of the reed, the contact wire 34 will move away from the contact wire 32 and the arm 28 will remain stationary during the initial portion of this counterclockwise stroke until the insulating strip 28 engages the end portion 30 of the arm 28 and swings the latter counterclockwise with the reed.

The means for driving the reed comprises an electromagnet having a laminated core 50 and winding 52. As shown in Fig. 6, the winding 52 is connected in series with a resistor 54 across a source of alternating voltage indicated as 6.3 v. A. C. The reed 10, 12 is connected to ground to which one terminal of the alternating current source is also connected so that when the contact 32 makes contact with the contact 34, the resistance 54 is shunted out of the energizing circuit for the winding 52, the latter then being connected directly across the alternating current source. The resistor 54 is of relatively high value compared to the impedance of the winding 52 so that no appreciable amount of current flows through the winding 52 when the contacts 32, 34 are open. The resistor 54, however, acts to suppress sparking across the contacts upon making and breaking the circuit. It will be noted that when the reed 10 is in its position of rest, its free end lies close to the end of the core 50, and that the center line of the reed is displaced from the center line of the core 50. The amount of this displacement is a substantial fraction of the oscillatory stroke of the end of the reed. Since the electromagnet 50, 52 is energized only during the clockwise swinging stroke of the reed, it is necessary, in order to make it possible to effect a net transfer of energy from the electromagnet to the reed, that the major part of the clockwise stroke of the reed be located in that portion of the magnetic field which applies an accelerating force to the reed. It will be clear that this is accomplished when the reed, in its rest position, is displaced a substantial distance counterclockwise of the magnetic center of the end of core 50.

The operation of the reed driving mechanism may best be explained by reference to the diagram, Fig. 7, wherein the end of the core 50 is diagrammatically shown, while the curves illustrate the displacement of the end of the reed relative to the core 50. Assuming that the reed has been set into low amplitude vibration by any suitable means, its displacement through a cycle of vibration will follow substantially the curve 7A.

At the origin of the curve 7A, the reed is in normal or rest position and travelling in a counterclockwise direction, during which time the contacts 32, 34 are separated. Shortly after the commencement of the clockwise stroke at the point c, the contacts will close and remain closed throughout the remaining portion of the clockwise stroke of the reed, that is, until the reed reaches the position d on the curve 7A. It will be understood, however, that after the reed passes the center line 7C of the core 50, the magnetic attraction of the core 50, instead of tending to accelerate the reed, tends to retard it. Such retarding action occurs during the movement of the

reed from the point e on the curve 7A to the point d on said curve. The length of time that the magnetic attraction is effective to accelerate the reed is thus represented by the dimension a, while the length of time during which the magnetic attraction retards the reed is represented by the dimension b.

Assuming that the frequency of the alternating current supplied to the winding 52 is high relative to the frequency of vibration of the reed, the magnetic field may be assumed to be constant, and thus, the amount of energy supplied to the reed by the electromagnet may be considered as a function of the difference between the dimensions a and b. This energy which is supplied to the reed by the electromagnet is of course dissipated in air friction and in the slight amount of internal friction in the leaf spring 12. If the energy supplied to the reed by the electromagnet is greater than that thus dissipated in friction, the amplitude of vibration of the reed must necessarily increase. If the system did not include some compensatory factor, the amplitude of vibration of the reed would tend to increase far beyond that desired, and thus buffer stops would have to be provided (as in the aforesaid application of Laurens Hammond), to limit the extent of vibration of the reed. The striking of the reed against such buffer stops would cause undesirable noise and would cause the vibration of the reed to depart from substantially simple harmonic or sine wave motion. Both of these effects are generally undesirable.

How the above undesirable effects are eliminated may be explained by reference to the curve 7B of Figure 7, which shows the instantaneous position of the reed when it is vibrating at high amplitude. Under these circumstances, the contacts 32, 34 close at the point c' and remain closed until the reed completes its clockwise stroke at the point d'. However, as the reed passes the center line 7C at the point e', the magnetic attraction of the core 50 acts to retard the reed. Thus, while the reed is moving from the point c' to the point e', energy is being supplied to the reed. On the other hand, as the reed moves from the point e' to the point d', energy is being taken from the reed by the electromagnetic system. The time during which energy is being supplied is thus represented by the dimension a', while the time that energy is being subtracted from the reed is indicated by the dimension b'.

By comparison of the dimensions a and b with the dimensions a' and b', it will be apparent that as the amplitude of vibration of the reed increases, the net energy added to the reed during each cycle decreases. Thus, the driving electromagnetic system in itself forms the braking or energy absorbing means effective to limit the amplitude of vibration of the reed because with increasing amplitude of vibration of the reed, the time during which energy is subtracted from the reed approaches in duration the time interval during which energy is being added to the reed, and thereby decreases the net amount of energy added to the reed necessary to overcome the frictional losses. From the foregoing, it will be apparent that while the voltage of the alternating current supplied remains constant and other conditions remain uniform, the reed will tend to vibrate at an equilibrium amplitude condition in which the net energy supplied to the reed is just sufficient to overcome the losses, mainly air friction losses. It will also be apparent that reasonably wide variations in the supply voltage

will produce relatively small variations in the amplitude of vibration of the reed.

The reed driving apparatus of the invention is of particular advantage because an alternating current source may be used to supply the necessary energy, although it will be apparent that the apparatus will also operate when the energizing source is direct current. When the energizing source is alternating current it should be of a frequency higher than that of the frequency of vibration of the reed. For example, an alternating current source of 25 to 60 C. P. S. or higher will be satisfactory provided the reed frequency is in the order of 7 C. P. S. This is a considerable economic advantage because of the elimination of a direct current supply system which would be required if the apparatus had to be operated on direct current.

While the electromagnet is disclosed herein as being located beyond the end of the reed, it may, for example, be located above or below the magnetic part of the reed, or the core of the electromagnet may be U-shaped with its poles adjacent opposite edges of the magnetic part of the reed. In each instance, the electromagnet should be so located with respect to the magnetic part of the reed that the center of attraction of the electromagnetic field (the position toward which the magnetic forces tend to move the reed), is displaced from the neutral position of the reed, the neutral position being the rest position assumed by the reed when the electromagnet is de-energized. The center of attraction of the electromagnet should also lie in the path of oscillation of the magnetic part of the reed, so that retarding as well as accelerating forces may be applied to the reed. In the following claims the terms "clockwise" and "counterclockwise" are not intended to have absolute, but instead merely relative, significance.

While I have shown and described a particular embodiment of my invention, it will be apparent to those skilled in the art that numerous modifications and variations may be made in the form and construction thereof, without departing from the more fundamental principles of the invention. I therefore desire, by the following claims, to include within the scope of my invention, all such similar and modified forms of the apparatus disclosed by which substantially the results of the invention may be obtained by substantially the same or equivalent means.

I claim:

1. In a vibrator, the combination of a reed having an oscillatory magnetic part, an electromagnet for driving said reed, said electromagnet having the center of attraction of its magnetic field located within the path of oscillation of said part but displaced clockwise with respect to said part when the reed is in neutral position, an energizing circuit for said electromagnet including a switch, and means operated by said reed to close said switch during substantially the whole of the clockwise stroke of said reed and to open said switch during the counterclockwise stroke of said reed.

2. In a vibrator, the combination of a reed having an oscillatory magnetic part, an electromagnet for driving said reed, said electromagnet having the center of attraction of its magnetic field positioned in the path of oscillation of said magnetic part so as to be capable of exerting both accelerating and retarding forces on said reed, an energizing circuit for said electromagnet including a switch, and means operated by said reed to

close said switch during substantially the whole of the forward stroke of said reed and to open said switch during the return stroke of said reed.

3. In a vibrator, the combination of a reed having an oscillatory magnetic part, an electromagnet for driving said reed, said electromagnet having the center of attraction of its magnetic field located in the path of oscillation of said part but to the side of said part when the reed is in neutral position, an energizing circuit for said electromagnet including a switch, and means controlled by said reed to close said switch during substantially the whole of the forward stroke of said reed and to open said switch during the return stroke of said reed.

4. In an electromagnetic vibrator, the combination of a vibratory reed having an oscillatory magnetic part, an electromagnet having its field traversed by said part, said electromagnet being so located with respect to said part that the latter is displaced from the center of attraction of the field of said electromagnet when the reed is in its neutral position, means for energizing said electromagnet including a switch, and means to close said switch during substantially the whole of the stroke of said reed in one direction and to open said switch throughout the stroke of said reed in the opposite direction.

5. In an electromagnetic vibrator, the combination of a vibratory reed having a magnetic part at its free extremity, an electromagnet positioned beyond but closely adjacent the path of oscillation of said magnetic part and having its center of attraction displaced from said part when said reed is in neutral position, and means for energizing said electromagnet during substantially all of the forward stroke of the reed and de-energizing said electromagnet throughout the return stroke of said reed.

6. In an electromagnetic vibrator, the combination of a vibratory reed having a magnetic part at its free extremity, an electromagnet positioned closely adjacent the path of oscillation of said magnetic part and having its center of attraction displaced from said part when said reed is in neutral position, and means controlled by said reed for energizing said electromagnet during substantially the whole of the forward stroke of the reed and de-energizing said electromagnet throughout the return stroke of said reed.

7. In an oscillatory element having a magnetic part, an electromagnet positioned closely adjacent the path of oscillation of said magnetic part and having its center of attraction displaced from said part when said element is in neutral position, and means for energizing said electromagnet during substantially the whole of the forward stroke of said element and de-energizing said electromagnet throughout the return stroke of said element.

8. In an oscillatory element having a magnetic part, an electromagnet having its field traversed by said part, said electromagnet being so located with respect to said part that the latter is displaced from the center of attraction of the field of said electromagnet when said element is in its neutral position, but passes through said center of attraction when oscillating at normal amplitude, and means for energizing said electromagnet including switch means closed during substantially the whole of the stroke of said element in one direction and opened throughout the stroke of said element in the opposite direction.
